US00D936916S

(12) **United States Design Patent** (10) **Patent No.:** **US D936,916 S**
Li (45) **Date of Patent:** **** Nov. 23, 2021**

(54) **TRANSMITTER OF DOG TRAINING COLLAR**

(71) Applicant: **Shenzhen Patpet Technology CO., LTD**, Shenzhen (CN)

(72) Inventor: **Linxian Li**, Beijing (CN)

(**) Term: **15 Years**

(21) Appl. No.: **29/707,811**

(22) Filed: **Oct. 1, 2019**

(51) LOC (13) Cl. **30-99**

(52) U.S. Cl.

USPC **D30/199; D10/104.1**

(58) **Field of Classification Search**

CLAIM

The ornamental design for a transmitter of dog training collar, as shown and described.

DESCRIPTION

FIG. 1 is a top right perspective view showing a new transmitter of dog training collar, showing my new design; FIG. 2 is a front elevation view thereof; FIG. 3 is a rear elevation view thereof; FIG. 4 is a top plan view thereof; FIG. 5 is a bottom plan view thereof; FIG. 6 is a side view thereof; and, FIG. 7 is an opposite side view thereof. The broken lines depict unclaimed features of the transmitter, shown for purposes of illustration, and form no part of the claimed design.
